[57] CLAIM

The ornamental design for a combined cap and sweatband, as shown and described.

DESCRIPTION

FIG. 1 is a bottom perspective view of a combined cap and sweatband showing my new design;

FIG. 2 is a top plan view of the sweatband, the cap removed for convenience of illustration;

FIG. 3 is a front elevational view thereof;

FIG. 4 is a left side elevational view thereof;

FIG. 5 is a right side elevational view thereof;

FIG. 6 is a bottom plan view thereof; and

FIG. 7 is a top plan view of FIG. 1.

FIG. 2.

FIG. 4.

FIG. 3.

FIG. 5.

FIG. 7.
